UNITED STATES PATENT OFFICE.

JOHN BARNERED KITTINGER, OF CENTRAL CITY, KENTUCKY.

HARROW.

SPECIFICATION forming part of Letters Patent No. 738,687, dated September 8, 1903.

Application filed June 6, 1903. Serial No. 160,393. (No model.)

To all whom it may concern:

Be it known that I, JOHN BARNERED KITTINGER, a citizen of the United States, residing at Central City, in the county of Muhlenberg and State of Kentucky, have invented certain new and useful Improvements in Harrows; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in harrows, and especially in an apparatus in which the harrows may be thrown automatically into operation and out of gear by suitable rotary mechanism, and comprises means whereby the harrow may be raised or lowered to adapt the machine for various conditions of ground.

The invention consists, further, in various details of construction and combinations and arrangements of parts, which will be herein-after fully described and then specifically defined in the appended claims.

The invention is illustrated in the accompanying drawings, in which—

Figure 1 is a top plan view of my improved harrow. Fig. 2 is a cross-sectional view showing parts in elevation. Fig. 3 is a rear view. Fig. 4 is a longitudinal section through the apparatus, showing parts in elevation. Fig. 5 is a detail view of the automatic coupling device, and Fig. 6 is a top plan view of the detail shown in Fig. 5.

Reference now being had to the details of the drawings by letter, A designates the axle of the machine, which supports a cross-piece A', to which the tongue B is fixed. Journalized upon said axle are the driving-wheels C, one of which has a geared wheel D fitted to the spokes of the wheel and adapted to drive mechanism for reciprocating harrows, as will presently be described. Fastened to said cross-piece A' are the beams E, (shown clearly in Fig. 1 of the drawings,) which beams have hinged thereto, as at E', the arms E'', in which the shaft F has bearings. Said shaft F has two downwardly-projecting arms F', (shown clearly in Fig. 3 of the drawings,) and se-

cured to each end of said shaft is a frame F'', containing harrow-teeth F'''.

G designates a collar, detail views of which are shown in Figs. 5 and 6, which collar is fixed to one of the arms of the shaft F, preferably in the location illustrated in Fig. 3 of the drawings, and fixed to the shank portion of said collar, which radiates out from the latter, are the blocks H, Figs. 5 and 6, which are apertured, as at H', one wall of each of said apertures being inclined, as at h, and I I designate blocks, which are pivotally mounted, as at I', upon the shank portion of said collar G. Each of said blocks I carries a spring-bar J, having a hook J' formed therein, adapted to engage over the inclined edge h of an aperture H' (shown in Fig. 5) for the purpose of locking the pivotal blocks I in a closed relation or in the position shown in Fig. 3 of the drawings. Each of the blocks I has fixed thereto a bar K, and upon the adjacent edges of the fixed blocks I and H are concaved recesses K', adapted to receive the T-shaped end L of the pitman L', a detail view of which is illustrated clearly in Fig. 6 of the drawings. Said pitman L' is pivoted to a pin L'', eccentrically mounted upon the face of the gear-wheel L'', the latter being fixed to rotate with a shaft M, mounted in suitable bearings upon the machine and being in mesh with the gear D, which is fixed to rotate with a driving-wheel, Fig. 4 of the drawings.

Mounted in suitable bearings N and N', Fig. 4 of the drawings, is a rock-shaft O, having an operating-handle O'. The outer end of said rod O has an eye O'', Fig. 5 of the drawings, through which the pitman L' has a play, and projecting from the rod O adjacent to said eye are two fingers O''', (shown clearly in Fig. 6 of the drawings,) and the free ends of said fingers are so positioned that as the shaft or rod O is rocked in one direction their free ends will engage the portions of the spring-hooks J and disengage the latter from the edges of the blocks H, thereby allowing the blocks I to fall by gravity into the position shown by dotted lines in Fig. 5 of the drawings.

Q designates a lever, which is fulcrumed at Q' upon a bracket-arm supported by the cross-piece A'. One end of said lever Q has an eye

through which the rock-shaft has a reciprocal movement, and when the free end of the lever Q is depressed the arms E², carrying the shaft F, may be raised from the ground, and 5 when in raised position said harrows, after the blocks I are thrown into the positions shown by dotted lines in Fig. 5, will be disconnected and idle. For holding the lever Q depressed a hook Q² is provided, under which the end 10 of the lever Q is swung, as will be readily understood.

R designates a cross-beam having an offset or dropped portion R', in which the tongue of the apparatus is positioned, and secured to 15 said beam R are the rods R², the lower ends of which have a play in the hollow boxes R³, which support the shaft R⁴, upon which are mounted the winged harrow-disks R⁵. The lower end of each rod R² carries a pin r, which 20 is mounted in elongated slots r' in the hollow boxes R³, whereby said rods may have a movement independent of the boxes.

R⁶ designates hollow boxes in which the shaft R⁴ has bearings, and rods R⁷, similar to 25 the rods R², have slight movements independent of the boxes R⁶, the upper ends of the rods R⁷ being fastened to bracket-arms R⁸. (Shown in Fig. 4 of the drawings.) Springs R⁹ are interposed between the hollow 30 boxes and the cross-beam and bracket-arms R⁸, respectively, whereby the rotary winged disks may yield slightly when the apparatus passes over uneven ground. Said beam R is supported upon the tongue by a plate S, 35 and a lever S' is pivoted at S² upon the tongue and, passing over the plate S, engages under a hook S³ to hold the plate to the tongue. If for any reason it is desired to 40 allow the beam to be raised from the tongue in case a large obstruction is met with, said lever S' may be thrown to one side and the beam allowed to be raised from the tongue. In order to permit a further vertical movement of the beam R, the arms T, which are 45 fastened to the beams, have hinged connection with the beams E, and sliding wedge-shaped blocks T' are mounted upon said beams E and are connected together by a bar T², and staples W and W' are provided, which 50 are mounted upon the adjacent ends of the beams E and arms T, respectively, and a lever V is pivotally mounted at V' upon a bracket-arm of the machine and has link connections V² with the bar T², whereby as 55 said lever is thrown in one direction or the other the wedge-shaped blocks T' may be thrown over the hinged connections between beams E and arms T or withdrawn in the position shown in full lines in Fig. 1. When 60 the wedge-shaped blocks are thrown to assume the positions illustrated by dotted lines in Fig. 1, they will be held from being thrown upward, and when in the position shown by full lines the arms will be allowed to rise 65 after the lever S' has been swung in order to clear the plate which supports the beam R.

The operation of my machine will be readily

understood when considered in connection with the foregoing and the drawings, and is as follows: As the machine is driven over a 70 field a reciprocating movement is imparted to the harrows, which are mounted upon the ends of the shaft F, said reciprocating movement being effected by the gear connections with the driving-wheel. In case it should be 75 desired to throw the reciprocating harrows out of gear the operator causes the shaft O to be rocked by throwing the lever O', connected therewith, sidewise. This movement of the lever O' will cause the fingers O³ to 80 bear against the spring-hooks J, clearing the latter from the edges of the blocks H, and the blocks I will fall by gravity, and by depressing the free end of the lever Q the shaft F may be raised so that the pitman L', still supported by the rod O, will reciprocate in the eye thereof without actuating the shaft F. When it is desired to throw the reciprocating harrows into operative relation, the free end 85 of the lever Q is raised and the shaft carried 90 thereby lowered, and as the T-shaped end of the pitman comes in contact with the bars K, fixed to the blocks I, the latter will be thrown into the positions shown in Fig. 5 of the drawings, in which the hooks J' will engage over 95 the edge of the block H and cause the shaft carrying the harrows to reciprocate.

By the provision of automatically-operated mechanism for throwing the harrows into gear and by the other features whereby the 100 forward part of the harrow carries the rotary disks an apparatus is produced which is adapted for use over both level and uneven fields.

While I have shown a particular form of apparatus illustrating features of my harrow, 105 it will be understood that I may make alterations in the detailed construction of the same, if found desirable, without departing from the spirit of the invention.

Having thus fully described my invention, 110 what I claim as new, and desire to secure by Letters Patent, is—

1. A harrow apparatus comprising an axle with wheels mounted thereon, beams supported by said axle, arms hinged to said beams, 115 a reciprocating shaft mounted in eyes at the ends of said hinged arms, harrows fastened to the ends of said shaft, gear connections between said shaft and one of said wheels, lever mechanism for raising said shaft, mechanism 120 for disconnecting the gear mechanism from said shaft, and means for raising the shaft, as set forth.

2. A harrow apparatus comprising a frame, 125 an axle, wheels mounted on said axle, beams supported by the axle, arms hinged to said beams, a shaft having a reciprocating movement in eyes at the ends of said arms, harrows fastened to the downwardly-extending ends of said shaft, a collar fastened to said shaft, fixed and pivotal blocks carried by said collar, a pitman having a T-shaped end adapted to be engaged by said blocks, connections 130 between said pitman and one of said wheels,

whereby a reciprocal movement may be imparted to the shaft, and means for disconnecting said blocks from the pitman, as set forth.

3. In combination in a harrow apparatus, 5 a frame, an axle, wheels mounted thereon, beams supported by said axle, arms hinged to the rear ends of said beams, a shaft supported by and having a reciprocating movement in said arms, harrows fastened to the 10 downwardly - extending ends of said shaft, a collar secured to said shaft, fixed and pivotal blocks mounted upon said collar, spring-hooks secured to said pivotal blocks and adapted to engage over the edges of apertures 15 in the fixed blocks, a pitman having T-shaped ends engaged by said blocks, gear connections between said pitman and one of said wheels, and means for disconnecting said pitman from said blocks, as set forth.
- 20 4. A harrow apparatus comprising a frame, an axle, beams supported by the axle, hinged arms upon said beams, a reciprocating shaft mounted in said arms, harrows secured to the ends of said shaft, a collar fastened to the latter, fixed and pivotal blocks mounted upon the collar, bars fastened to said movable blocks, spring-hooks upon the movable blocks 25 designed to engage over the edges of apertures in the fixed blocks, and a pitman having a T-shaped end adapted to engage said bars to throw the blocks into a closed relation, and means for disconnecting the blocks, as 30 set forth.

5. A harrow apparatus comprising a frame, an axle and wheels thereon, beams supported by the axle, hinged arms upon said beams, a reciprocating harrow - supporting shaft mounted in said arms, a collar secured to said shaft, fixed and pivotal blocks mounted upon said collar, bars fastened to said pivotal blocks, spring-hooks secured to the pivotal blocks designed to engage the fixed blocks, a pitman having a T-shaped end designed to be held by said blocks, a rock-shaft having an eye at one end through which said pitman 45 has a reciprocating movement, and fingers projecting from said shaft designed to engage and release said spring-hooks from the fixed blocks, as set forth.

6. In a harrow, the combination with the 50 axle and wheels thereon, of a tongue, parallel beams supported by said axle, a cross-beam R having a dropped portion engaged by said tongue, arms secured to said cross-beam and having hinged connections with said parallel beams, disk-harrow-supporting shafts yieldingly mounted upon said cross - beam, and movable wedge-shaped members for holding said arms in alinement with said parallel beams, as set forth.

In testimony whereof I hereunto affix my signature in presence of two witnesses.

JOHN BARNERED KITTINGER.
